UNITED STATES PATENT OFFICE.

FRANK F. McCARLLEY, OF SISTERSVILLE, WEST VIRGINIA.

SWING.

No. 857,653.

Specification of Letters Patent.

Patented June 25, 1907.

Application filed September 16, 1904. Serial No. 224,694.

To all whom it may concern:

Be it known that I, FRANK F. McCARLLEY, a citizen of the United States of America, residing at Sistersville, in the county of Tyler 5 and State of West Virginia, have invented certain new and useful Improvements in Swings, of which the following is a specification, reference being had therein to the accompanying drawing.

10 This invention has relation to swings, and more particularly to that class which are adapted for use upon verandas and lawns, and the object of this invention is to provide a novel form of swing which may be readily 15 supported in a frame or swung from the ceiling of a veranda or porch.

Another object of this invention is to provide a portable swing which will be adjustable whereby the same may be inclined or adjusted 20 to form a chair, and I have provided novel means whereby the swing proper may be supported and swiveled in a suitable frame for use in connection with lawns.

The invention further contemplates providing 25 a swing which can be made of light weight iron of standard dimensions, and the swing proper can be disassembled whereby a compact form is obtained for transportation, the parts being readily assembled when it is 30 desired to construct the swing. By constructing the same of light metal of standard sizes, the cost of manufacture is reduced to a minimum, and a strong and durable swing obtained.

35 The invention finally consists in the novel construction, combination and arrangement of parts to be hereinafter described and specifically pointed out in the claims.

In describing the invention in detail, reference 40 is had to the accompanying drawings, forming a part of this application, in which the figure illustrates a perspective view of my improved swing.

In the drawing accompanying this application, I have illustrated the swing as being 45 mounted in a lawn stand, but I do not care to limit myself to the specific use of the swing in this stand, as the same may be detached and supported from suitable hooks in the ceiling 50 of a veranda or porch, or, if it be desired, the stand may be placed upon the veranda or porch when it is not desired to disfigure the ceiling thereof with hooks or like supports upon which the swing may be supported.

55 In the view illustrating my invention, the reference characters A and B designate a set

of metallic strips, each set comprises two strips which form the base of the stand or frame in which my improved swing is mounted. These metallic strips support an inverted U-shaped frame C, which is preferably made of a pipe bent to conform to the shape described, the ends of the pipe being formed with a contracted portion which is inserted between the strips comprising the sets A and B of the base, and the ends of the pipe C are riveted to the strips as indicated at D. The frame or pipe C is further supported by an angularly disposed brace E, the one end of which brace surrounds the pipe or frame C, while the other end of each brace is riveted between the metallic strips as indicated at F. The base of the inverted U-shaped frame C is spaced apart or braced by a transverse angular strip G, the ends of which are secured to the pipe or frame C.

The reference character H designates a bolt which is secured in the top of the frame C and upon this bolt is swiveled or pivotally mounted my improved swing.

The swing comprises an inverted U-shaped member 1, which is provided with an aperture 2, whereby the same may be mounted upon the bolt H. The depending sides of the member 1 are provided with a plurality of apertures 3, and in these apertures are pivotally mounted angularly-disposed frames 4, 4, which constitute the sides of the swing, the lower ends of these frames being spaced apart by the bars 5, and these bars form side rails or arm rests for the occupant of the swing.

The reference numeral 6 designates a connection between the bars 5 and the frames 4, and when these bars are connected together, the foot rails 7, 7 and the back rails 8, 8, are connected thereto. These rails are spaced apart by the cross rods 9, 10, 11. To the protruding ends of the cross rod 10 I secure rearwardly extending bars 12, 12 which have their outer ends braced together by the cross rod 14, and said bars are supported from the lower ends of the back rails as designated at 15, 15, and where this connection is made, the toothed bars 16, 16 are connected, the teeth of which are adapted to engage the pins 17, 17 carried by the bars 5.

By the construction just described, it will be seen that the foot support and the back of the swing are adjustable, and the position of the back and foot supports being determined by the toothed bars which engage the bars 5, it will be observed that the back and the foot

rests may be inclined at any angle desired, and in order to support the occupant within the swing, a suitable covering of canvas or like material may be connected to the cross rods 11, 10 and 9. It will also be seen that the position of the swing in relation to the inverted U-shaped member 1 may be adjusted either one of the apertures 3 being employed when different heights are desired for positioning the swing. The construction employed by me permits of the swing being turned around at any angle desired, at the same time swinging within the member 1, and I wish it to be understood that while I have herein described the swing in its frame as being made of metal, the same may be readily constructed of light strips of wood and that any other suitable means may be employed for adjusting the inclination of the back and foot rests of the swing.

It will be noted that various changes may be made in the details of construction without departing from the general spirit of my invention.

Having fully described my invention, what I claim as new and desire to secure by Letters Patent is:—

1. The combination with an inverted U-shaped supporting-frame, of a swing-frame suspended from said supporting-frame, and a swing carried by the swing-frame and comprising supporting-bars adjustably-connected at their upper ends to the swing-frame, arm-rest bars pivotally-connected to said

supporting-bars, foot-rails pivotally-connected to the forward ends of the arm-rest bars, cross-rods connecting said foot-rails, side-bars pivotally-connected at their forward ends to the foot-rails, back-rails pivotally connected to the arm-rest bars and the side-bars, a cross-rod connecting said back-rails adjacent their upper ends, pins carried by the arm-rest bars, and toothed racks to engage with said pins, substantially as described. 35

2. In a device of the class described, a supporting frame, a swing frame suspended from said supporting frame, and a swing carried by said swing frame and comprising supporting bars detachably connected at their upper 40 ends to the swing frame, arm rests pivotally connected to said supporting bars and provided respectively with lateral pins, foot rails pivotally connected to the arm rests, transverse rods connecting said foot rails, 45 side bars movably connected to the foot rails, back rails movably connected to the arm rests and side bars, a transverse rod connecting said back rails, and bars swinging from said swing frame and provided with 50 spaced teeth adapted to engage with said lateral pins. 55

In testimony whereof I affix my signature in the presence of two witnesses.

FRANK F. McCaulley.
